UNITED STATES PATENT OFFICE

JOHN GEORGE DOUGLAS, OF LEAGRAVE, LUTON, ENGLAND

MACHINE FOR POLISHING OR GRINDING CAM TRACKS AND LIKE SINUOUS SURFACES

Application filed April 1, 1931, Serial No. 526,890, and in Great Britain May 6, 1930.

This invention relates to improvements in machines for polishing or grinding cam tracks and like sinuous helical surfaces. The invention is particularly useful where it is required to polish or grind the tracks or grooves of worms or cams in which the pitch is not constant and/or in which the groove is terminated at one or both ends by solid metal and/or which have been generated to engage with a conical peg or a roller adapted to move in a non-rectilinear path, for instance as adopted in the production of automobile and the like steering gears. The practice adopted heretofore in finishing or polishing these worm spindles or cam grooves shafts is to execute the operation by hand by reason of the difficulty with machines of ensuring that the polishing mop will during its rotation follow accurately the predetermined non-constant helical path due to the varying pitch, depth of groove and flank angles. My present invention provides a machine in which regularity and accuracy in polishing or grinding is obtained irrespective of whether the cam like or sinuous surface to be treated is of uniform pitch throughout or of varying pitch, the object of my invention being to provide improved and faster means with such a machine which will obviate the necessity of hand polishing and will avoid adjustments by the operator during the polishing or grinding operation.

In a polishing or grinding machine according to my invention the pitch of the work determines the translating movement necessary for the polishing or grinding member to act along the faces of the work to be polished or ground.

A holder is provided for the work which is translatable movably supported in such manner that the pitch of the cam or like surfaces of the work effects a movement of translation of the holder automatically synchronously with the change in surface of the work being polished or ground.

In the preferred form of my invention the work is readily detachably held in a holder suspended pivotally from a support so that the work presses downwards and laterally against the polishing or grinding tool bob or

mop, the said holder being free to move under the cam action influence of the work against the tool bob or mop.

In order that my invention may be clearly understood and readily carried into effect, I have appended hereto two sheets of drawings illustrating embodiments thereof and wherein,

Fig. 1 is a perspective view showing the machine in use. 60

Fig. 2 is a detail broken perspective view showing an alternative method of carrying the work holder.

Figs. 3 and 4 are detail views showing alternative forms of mops. 65

Fig. 5 is a part sectional side elevation.

Figs. 6 and 7 are longitudinal sections through the mandrels for holding the work.

Referring to the drawings I can employ a mop spindle 1 of usual type, the mop 2 of which can be charged with abrasive emery powder or the like on its face, the spindle preferably being on a horizontal axis in a plane between the ends of an upright pillar 3 adjustably supported by a base 4 which can be secured fast to the floor. Supported at its centre across the upper end of the said pillar is a wide U shaped bracket 5 which is carried by a collar 6 which can be adjusted up and down and angularly around the pillar 3 to a desired height and angular position. This arrangement allows the height of the said bracket to be set so as to bring the centre line of the work to be polished in the plane containing the axis of the said mop spindle. The U shaped bracket 5 can swivel about a horizontal axis in all its positions so that the said bracket 5 can be swung round the pillar 3 and also assume any angle relative to the axis of the mop carrying spindle as may be necessary. 25

For this purpose the centre of the bracket 5 can pivot on a pin 7 fixed to the collar 6, a pair of studs 8 threaded into the collar and engaged in arcuate slots 9 in the bracket 5 concentric with the pin 7 providing a means of 30 securing the said bracket in selected angular relationship to the pillar 3.

The free ends of the side arms of the said U shaped bracket 5 are formed with bosses 10 bridged by a guide shaft 11, and this guide 100

shaft which is arranged parallel to the axis of and above the plane of work has slidable on it a pair of depending arms 12 which at one end are preferably integral with or attached to a sleeve 13 forming a U shaped frame, the sleeve 13 preferably containing ball bearings so that the frame can slide freely along the guide shaft and can also swing easily round such shaft. The free ends of each of said arms 12 of the frame depend beneath the said guide shaft 11 and they respectively support co-axial mandrels 14 and 14a free to rotate in the arms 12 and adapted to support between them the work 15.

16 One end of one of the mandrels is capable of being withdrawn by a milled head 16 against a coiled compression spring 23 inside a housing 18 on the appropriate arm 12 so that the work can be inserted between the mandrels. The other mandrel 14a is adapted to be continually rotated at any suitable speed preferably by a worm 24 and worm wheel 25 accommodated in a housing 19 on the other arm 12 of the said frame and driven by a flexible shaft 20 from the overhead works of the shop or by an electric motor, or any other suitable source of power. A driving shaft 21 passes through this mandrel and rotates with the mandrel but can slide axially on feathers 22 in the mandrel. The inner end of this driving shaft 21 of the mandrel is formed to engage with the serrations or other suitably shaped parts formed in an end face or in the bore of the cam or other work 15 being polished. An exchangeable distance piece 26 is threaded into the inner end of the shaft 21 to enable different axial dimensions of work to be compensated for. The inner end of the other mandrel 14 is also suitably formed to receive one of the ends of the work.

17 A substantially horizontal arm 27 is pivoted at one end to a lug 28 on the said U shaped bracket and this arm is formed near its free end with a slot 29 which can be engaged over a transverse rod 30 on the said depending work carrying frame 12 for holding the work clear of the polishing mop 2 to enable the spring loaded mandrel 14 to be retracted to release the work.

18 When polishing a worm of a steering pillar of a motor road vehicle as shown in Fig. 1 or for like work, the pillar 3 is adjusted to the required extent relative to the base 4 to set the work with relation to the mop spindle so that when one face of the mop 2 is in contact with one side of the flank of the groove in the cam or worm the said depending frame 15 does not lie vertically but forms an angle with the said upright pillar 3 so that according to such angle the worm is pressed by gravity against the appropriate face of the mop and with such degree of force as may be required. This pressure may be enhanced by a tension spring connected to the depending frame 12 and to the centre of the U shaped bracket 5. The

said U shaped bracket is swung round a vertical axis constituted by the said pillar so that the said face of the mop 2 is in contact radially right across the selected side of the face of the groove in the cam. The frame 12 and bracket 5 are also set at such angle as may be necessary to obtain an axially directed pressure between the said face of the mop and the appropriate side of the flank of the cam shaped part of the work.

70 When the work is ready the operator disengages the slot 29 of the arm 27 from the transverse rod 30 on the frame 12 and by means of a pair of handles 31 extending from the frame 5 lowers the work on to the mop, the mandrel 14a rotating the work so as to feed the work along the mop, the sliding ball bearing support of the said frame on the guide shaft 11 permitting this feeding.

75 The polishing then proceeds without the workman having to touch the said frame or handles, the revolving worm or like work with its helical groove causing the said frame to slide along the said guide shaft at such varying speed as the variable pitch of cam or worm itself may require.

80 As the pressure between the mop face and the side of cam track is constant at all points, and rotation of the cam or other like work is constant, polishing or grinding of one side of the cam track is perfectly regular and the formation, helix angles, side angles of track etc., are exactly the same after polishing or grinding as before such operation.

85 When the work has traversed across the mop from one end to the other, the workman swings the said frame 5 up and away from the mop so that the slot 29 of the arm 27 drops over the said transverse rod 30 of the frame, and holds the frame stationary clear of the mop. The work is then reversed end for end, and the other side of cam track is polished or ground in the same way.

90 Alternatively the mop 2 can be formed with two inclined working faces and a working periphery as shown in Fig. 4 so that both sides of groove are polished or ground at the same time. In this case both sides of the mop are coated with a suitable abrasive.

95 An alternative form of bracket and depending frame in which the frame does not slide along a guide shaft, but swings can be adopted. For this purpose the sliding movement of the said frame can be replaced by a parallel link like motion as shown in Fig. 2 by connecting the ends of a rod 32 passing through the upper corners of the said frame 12 by a pair of depending parallel links 33 to the said bracket 5.

100 The pillar 3 can be adjusted along a vertical plane in a slot 34 in the base 4 by means of a hand wheel 35 fixed on a shaft 36 threaded into a collar on the lower end of the pillar 3. The pillar can be turned axially in said collar and clamped by a nut 37 acces-

sible by a tommy bar through an opening 38 in the base 4.

What I claim is:—

1. In a polishing or grinding machine a 5
mop or tool holder a pair of axially aligned
spaced work holders between which the work
is adapted to be held, means with one of said
holders for rotating the work axially, a sub-
stantially horizontal guide above said hold-
ers, the said holders being suspended from
beneath said guide by means freely slideable
10 along said guide whereby the work by its
engagement with the tool or mop constitutes
the sole means of imparting a movement of
15 translation to the work holders.

2. A polishing or grinding machine com-
prising a bracket, a rod supported substan-
tially horizontally across said bracket, a work
holder rotatable at one end about said rod
20 and free at its other end, a pair of spaced
work receiving devices at the free ends of
said holder, means with one of said devices
for rotating the work, a tool or mop for
engaging the work located beneath said rod,
25 the said holder being freely slideable along
said rod, a pillar, a member slidably adjust-
able along said pillar and means angularly
adjustably connecting said bracket to said
pillar.

3. A polishing or grinding machine com-
prising a bracket, a rod supported substan-
tially horizontally across said bracket, a work
holder rotatable at one end about said rod
and free at its other end, a pair of spaced
35 work receiving devices at the free ends of
said holder, means with one of said devices
for rotating the work, a tool or mop for
engaging the work located beneath said rod,
and links pivoting said rod to said bracket so
40 that the said work holder is free to move in
a direction substantially parallel with the
axis of the work, a pillar, a member slidably
adjustable along said pillar, and means an-
gularly adjustably connecting said bracket
45 to said pillar.

4. A polishing or grinding machine com-
prising a bracket, a rod supported substan-
tially horizontally across said bracket, a work
holder rotatable at one end about said rod
50 and free at its other end, a pair of spaced
work receiving devices at the free ends of
said holder, means with one of said devices
for rotating the work, a tool or mop for
engaging the work located beneath said rod,
55 the said holder being freely slideable along
said rod, a pillar, a member slidably adjust-
able along said pillar and means angularly
adjustably connecting said bracket to said
pillar, a base for said pillar and means
60 for adjusting the pillar relative to said base.

5. A polishing or grinding machine com-
prising a bracket, a rod supported substan-
tially horizontally across said bracket, a work
holder rotatable at one end about said rod
65 and free at its other end, a pair of spaced

work receiving devices at the free ends of
said holder, means with one of said devices
for rotating the work, a tool or mop for en-
gaging the work located beneath said rod,
and links pivoting said rod to said bracket 70
so that the said work holder is free to move
in a direction substantially parallel with the
axis of the work, a pillar, a member slidably
adjustable along said pillar, and means an-
gularly adjustably connecting said bracket to 75
said pillar, a base for said pillar and means
for adjusting the pillar relative to said base.

In witness hereof I have signed this specifi-
cation.
